LIGHTNING ARRESTER SYSTEM

Filed Jan. 26, 1925

2 Sheets-Sheet 2

UNITED STATES PATENT OFFICE.

HENRY HEESE, OF JERSEY CITY, NEW JERSEY.

LIGHTNING-ARRESTER SYSTEM.

Application filed January 26, 1925. Serial No. 4,876.

This invention relates to new and useful improvements in lightning arrester systems particularly adapted for use upon chimneys, stacks and the like.

One of the important objects of the present invention is to provide a lightning arrester system wherein a single wire is employed to provide the ground wire, and the conductor portion which encircles the upper portion of a chimney and is connected to the lower ends of a plurality of lightning rods, thus obviating the necessity of providing a permanent connection between the conductor portion of the wire and the ground wire, or further employing a splice such as is now generally used for this particular purpose.

A further object of the invention is to provide a lightning arrester system of the above mentioned character, wherein a detachable connection is provided for the free end of the conductor portion of the wire and the portion thereof which extends along the outer wall of the chimney.

A further object is to provide a lightning arrester system of the above mentioned character, which is of such construction as to permit the same to be readily and easily installed in position on a chimney, either after the construction thereof or during the construction of the same.

A still further object is to provide a lightning arrester system of the above mentioned character, which is simple in construction, inexpensive, strong and durable and further well adapted for the purposes for which it is designated.

Other objects and advantages of this invention will become apparent during the course of the following description.

In the accompanying drawings forming a part of this specification, and in which like numerals designate like parts throughout the same:

Figure 1 is a diagrammatic view of the lightning arrester system embodying my invention.

Figure 2 is a similar view of another form adapted to be used in conjunction with chimneys of greater height.

Figure 3 is a detail perspective view of the detachable connection between the free end of the conductor portion and the adjacent portion of the ground wire.

Figure 4 is a fragmentary detail illustrating the connection between the conductor

portion of the wire and the lower end of one of the lightning rods.

Figure 5 is a detail of the connection between the upper end of the additional ground wire, and the upper conductor wire.

Figure 6 is a detail of the connection between the free ends of the lower conductor wire and the intermediate portion of the first mentioned ground wire, and

Figure 7 is a detail of the ground connection.

With reference to Figure 1 of the drawings, the lightning arrester rods are illustrated at 1. Any number of these rods may be provided as is desired and in the present instance, the chimney has associated therewith four of such rods. The number of rods to be used depends upon the size of the chimney. Each of the rods is preferably in the form of an elongated copper member which terminates at its upper end in a point. The upper ends of the rods are adapted to be disposed vertically above the top of the chimney.

A single wire or cable 2 extends along the wall of the chimney and the upper portion thereof encircles the upper portion of the chimney as clearly illustrated in Figure 1 to provide the conductor portion 3. The free end 4 of the conductor portion 3 is connected to the adjacent portion of the vertically extending wire 2 through the medium of the detachable connection illustrated generally by the numeral 5. The detachable connection comprises the upper and lower complementary sections 6 and 7. These sections

are provided with the laterally extending ears 8 and 9 respectively, with which are associated the fastening screws 10. The inner end of the upper section 6 is provided with an opening 11 receiving the upwardly disposed tongue 12 formed on the inner ends of the lower section 7 whereby the inner ends of the sections are interlocked in a detachable manner. The inner opposed faces of the complementary sections are provided with the transversely extending cooperating grooves whereby means is provided in the central portion of the connection for receiving and securing the free end 4 of the conductor portion 3 of the single wire or cable.

A diagonally arranged opening is formed in the outer portion of the connection 5 by providing a pair of complementary grooves in the inner opposed faces of the outer portions

105

110

105

of the sections 6 and 7 and extending through this diagonal opening is the adjacent portion of the conductor portion 3 as is more clearly illustrated in Figure 3.

5 The upper section 6 of the detachable connection 5 is provided with the upwardly extending internally threaded socket member 13 for detachably supporting the lower threaded end of one of the lightning arrester 10 rods. The lower ends of the other lightning arrester rods are electrically connected to the conductor portion 3 which encircles the upper portion of the chimney 1 through the medium of the detachable connection illustrated generally at 14 with reference more 15 particularly to Figure 4.

The above mentioned detachable connection 14 includes the complementary upper and lower sections 15 and 16 respectively, 20 the intermediate portions thereof being provided with cooperating channels or grooves which extend transversely whereby a circular opening is formed for receiving the conductor portion 3. The sections are secured at one end by means of the threaded bolt 17, the opposite ends of these sections being detachably connected through the medium of the tongue and slot 18 and 19 respectively. The upper section 15 of each of 30 the connections 14 is provided with the upwardly extending internally threaded socket member 20 similar to the socket member 13 for receiving the lower threaded ends of the other lightning arrester rods.

35 The grounding means includes a bucket 21 which is embedded in the ground, the same being filled with charcoal or the like as illustrated at 22 for the purposes well known in the art. The ground wire 3 has 40 its lower end encircling the metallic bucket 21 as illustrated at 24, a detachable connection 25 being provided at the juncture of the encircling portion 24 and the vertically disposed portion of the ground wire. The 45 upper end of the ground wire which extends above the surface of the ground is detachably connected to the lower end of the elongated wire or cable 2 as indicated generally at 26.

The system as shown in Figure 1 is adapted 50 to be used in conjunction with chimneys or stacks of approximately one hundred feet in height or less than such height. Where the chimney or stack is of a greater height, an additional conductor wire and ground 55 wire is required, and to this end, I provide a wire or cable 27, the same being adapted to extend vertically along the outer wall of the chimney at a point diametrically opposite the wire 2. The upper end of the cable or 60 wire 27 is adapted to be electrically connected to the conductor portion 3 which encircles the upper portion of the chimney through the medium of the detachable connection 28 the latter being identical with 65 the detachable connection 5 and cooperating

with the wire or cable 27 and the conductor portion 3 in the same manner as heretofore described.

70 Encircling the intermediate portion of the chimney is the lower conductor cable or wire 29. The free ends thereof are disposed in suitable openings provided therefor in the detachable connection designated generally by the numeral 30, one of the sections of said connection being illustrated at 31 with reference more particularly to Figure 6. The connection 30 is also provided with a vertically disposed opening for receiving the intermediate portion of the wire 2 whereby an electrical connection between the lower 80 conductor cable and the wire 2 is provided. The intermediate portion of the cable or wire 27 is electrically connected to the lower chimney encircling conductor cable 29 by the detachable connection designated generally 85 by the numeral 32, one of the sections thereof being indicated at 33 with reference more particularly to Figure 5.

90 The lower end of the vertically extending cable or wire 27 is adapted to be connected to a ground wire 34 which is similar to the ground wire 23, a detachable connection 35 the construction of which is identical with the structure of the connection 26 heretofore described, providing a means for connecting the respective ends of the wires 27 and 34 together.

100 As many additional conductor wires and vertically extending wires as well as conductor wires are provided in connection with the lightning rods depending upon the height of the chimney or stack with which the lightning arrester system embodying the present invention is associated.

105 It will thus be seen from the foregoing description, that a lightning arrester system for chimneys, towers, monuments and smoke stacks has been provided which may be readily installed in position thereon either during the building of the structure or after 110 the same has been completed, the system being at all times positive and efficient in carrying out the purposes for which the same is designated.

115 Furthermore, the simplicity in which the present system is constructed enables the several parts to be readily assembled or disassembled and the use of splicers or other permanent fastening means between the various wires is entirely eliminated.

120 While I have shown the preferred embodiment of my invention, it is to be understood that various changes in the size, shape and arrangement of parts may be resorted to without departing from the spirit of the invention and the scope of the appended claims.

125 Having thus described the invention, what I claim is:—

130 1. In a connection for use in conjunction

with a lightning arrester system for chimneys which includes a plurality of lightning rods, a ground wire extending along the outer wall of the chimney, the upper portion thereof encircling the upper portion of the chimney to provide a conductor wire, said connection comprising a pair of upper and lower complementary sections, the upper section being provided with a 10 socket for receiving and supporting the lower end of a lightning rod, the inner opposed faces of said sections having cooperating transversely extending grooves formed therein for receiving the free end 15 of the conductor wire, the inner opposed faces of the complementary sections being further provided with diagonally arranged grooves for receiving the adjacent portion of the ground wire, and means for detachably securing the complementary sections together.

2. In a connection for use in conjunction with a lightning arrester system for chimneys which includes a plurality of light-

ning rods, a ground wire extending along 25 the outer wall of the chimney, the upper portion thereof encircling the upper portion of the chimney to provide a conductor wire, said connection comprising a pair of upper and lower complementary sections, the upper section being provided with a socket for receiving and supporting the lower end of a lightning rod, the inner opposed faces of 30 said sections having cooperating transversely extending grooves formed therein for receiving the free end of the conductor wire, the inner opposed faces of the complementary sections being further provided with diagonally arranged grooves for receiving the adjacent portion of the ground wire, 35 means for detachably securing the complementary sections together, said last mentioned means comprising an interlocking and interfitting means arranged at one end of the sections, and securing bolts associated 40 with the other end of said sections.

In testimony whereof I affix my signature.

HENRY HEESE.
